WILLIAM G. HESLEP AND THOMAS A. COCHRANE, OF JAMES-TOWN, CALIFORNIA.

Letters Patent No. 91,627, dated June 22, 1869.

IMPROVED ORE-WASHER AND CONCENTRATOR.

The Schedule referred to in these Letters Patent and making part of the same.

To all whom it may concern:

Be it known that we, WILLIAM G. HESLEP and THOMAS A. COCHRANE, of Jamestown, county of Tuolumne, State of California, have invented an Improved Concentrator; and we do hereby declare the following description and accompanying drawings are sufficient to enable any person skilled in the art or science to which it most nearly appertains, to make and use our said invention or improvement, without further invention or experiment.

Our invention relates to a new and improved device for concentrating or separating and gathering in a body, sulphurets, after the ore has been put through the mill; and

It consists of a series of troughs, having an inclination in opposite directions, so that the pulp, after being fed to the upper trough, will be carried from one to the other, back and forth, discharging the sulphurets into each lower trough successively, while the sand and debris are gradually separated from it, and carried away through spouts at the lower ends of the troughs.

To more fully illustrate and explain our invention, reference is had to the accompanying drawings and letters marked thereon, forming part of this specification, of which—

Figure 1 is a side elevation.

Figure 2 is an end view of the troughs.

Figure 3 is a top view.

Similar letters of reference in each of the figures indicate like parts.

A is a foundation, or frame, having upright posts B' at each corner.

Across each end of the frame, between these posts, extend supports *aa*, which serve to uphold the troughs D D D'.

These troughs increase in width from the bottom to the top, each one being wider than the one below it, and are set at an incline, so that each one will stand at an opposite angle to the one directly above and below it.

The bottoms of the troughs are made of copper, or other metal having an affinity for mercury, and are amalgamated so as to catch the particles of gold in their passage along the bottom of the troughs.

Upon the top of the posts B B', and placed lengthwise of the frame, is a tank, C, into which fresh water is constantly fed from a trough above, shown in red.

Hollow posts, E E, having their lower ends closed, connect with the tank C at each end, and pass down beside the upright posts B'.

The pipes *ee* lead the water from the hollow posts, and discharge it at the upper end of each trough, where it catches and carries off the refuse matter.

The lower ends of the troughs are open, and lead

into vertical spouts G G', which convey the water and refuse matter to the discharging-trough H beneath.

Near the lower end of each of the troughs the bottom is divided, leaving the portion *d* free to move in ways back and forth, so that it may be set so as to leave an opening of any desired width, through which the sulphurets may fall to the trough beneath.

The pulp or tailings to be treated pass into the elevated end of the upper trough D, through the pipe shown in red, and pass down to the opposite end, where the sulphurets and heavy particles fall through the opening to the upper end of the second trough, the sand and debris being carried through the vertical spouts and discharged at the bottom.

When the sulphurets, or portion of the pulp which has passed to the second trough, strikes the upper portion of the trough, the fresh water from the pipes *ee* carries it down the trough, and the particles of gold will cling to the amalgamated surface, while the sulphurets, more thoroughly cleaned, will fall, as before, to the next trough, and the sand and debris, as before, pass off through the vertical spout.

Thus the sulphurets are carried down the inclined troughs one after another, and as they descend, are more thoroughly cleansed, until they finally pass into the spout I, and are deposited into any suitable receptacle.

Any number of inclined troughs may be used necessary to completely separate the sulphurets and refuse matter, and they may be set at a greater or less incline, according to circumstances.

By the use of this device, we are able to separate the sulphurets from the refuse matter without the use of blankets or other apparatus.

Having thus described our invention,

What we claim, and desire to secure by Letters Patent, is—

1. The inclined troughs D D, having amalgamated bottoms, and having the section *d* moving in ways so as to form an opening, through which the sulphurets may pass to the troughs below, the whole arranged substantially as described.

2. The perpendicular spouts G G, for carrying off the surplus water and refuse matter, substantially as and for the purpose herein described.

3. The tank C, hollow posts E E, and pipes *ee*, for introducing water to the heads of the troughs, substantially as and for the purpose described.

In witness whereof, we have hereunto set our hands and seals.
